United States Patent Office

Des. 198,864
Patented Aug. 11, 1964

198,864

STAMP-AFFIXING MACHINE

Robert Henry Relly, Cincinnati, Ohio, assignor to Stamp-Affixing Machine, Inc., Cincinnati, Ohio, a corporation of Ohio

Filed July 25, 1963, Ser. No. 75,965

Term of patent 14 years

(Cl. D52—2)

I claim:

The ornamental design for a stamp-affixing machine, as shown and described.
